US0D1077852S

(12) United States Design Patent (10) Patent No.: US D1,077,852 S
(45) Date of Patent:  Jun. 3, 2025

(54) DISPLAY SCREEN OR PORTION THEREOF WITH ICON OF A GAMING MACHINE

(71) Applicant: LNW Gaming, Inc., Las Vegas, NV (US)

(72) Inventor: Gregory Tay Tobey, Crystal Lake, IL (US)

(73) Assignee: LNW Gaming, Inc., Las Vegas, NV (US)

() Term: 15 Years

(21) Appl. No.: 29/896,813

(22) Filed: Jul. 7, 2023

(51) LOC (15) Cl. 14-04

(52) U.S. Cl.

USPC D14/490

(58) Field of Classification Search

USPC D14/485-495

(57)

CLAIM

The ornamental design for a display screen or portion thereof with icon of a gaming machine as shown and described.

DESCRIPTION

The FIGURE is a front view of a display screen or portion thereof with icon of a gaming machine showing my new design.

The peripheral boundary broken lines showing the display screen or portion thereof form no part of the claimed design.

1 Claim, 1 Drawing Sheet
